UNITED STATES PATENT OFFICE

GUSTAV C. PEARSON, OF DENVER, COLORADO, ASSIGNOR TO GARDNER-DENVER COMPANY, OF DENVER, COLORADO, A CORPORATION OF DELAWARE

DRILL SHARPENER

Application filed August 6, 1930. Serial No. 473,437.

The object of the present invention is to provide novel, simple and effective means for cleansing scale and like accumulations from the dies of metal forging machines, more particularly drill sharpeners, said means taking the cleansing fluid from the die operating motor and being so constructed that it will not interfere with the effective action of such motor.

10 In the accompanying drawings:

Figure 1 is a front elevation of a rock drill sharpener equipped with the cleansing mechanism.

Figure 2 is a top plan view of the same, 15 with portions broken away in order to show the cleansing fluid directing means.

Figure 3 is a sectional view on the line 3—3 of Figure 2.

Figure 4 is a vertical sectional view showing the dies when fully open.

Figure 5 is a similar view but showing the dies closed.

Figure 6 is a detail horizontal sectional view on an enlarged scale and on the line 25 6—6 of Figure 4.

In the embodiment disclosed a suitable base is employed upon which is positioned a fluid actuated motor, the same comprising a cylinder member 7 having a lower piston 20 chamber 8 and an upper piston chamber 9. A head 10, secured on the base, closes the upper end of the piston 9, and is secured to the cylinder member by bolts 11.

This head 10 constitutes a carrier or holder 35 for fixed dies. Thus in the present embodiment there is a central die 12, and as shown in Figure 1, other dies 13 are located on opposite sides of the die 12. Cooperating with the head 10 is an upper vertically movable die carrier 14 carrying a central die 15 that cooperates with the die 12, and also carrying side dies 16 that cooperate with the dies 13. The upper die carrier 14 is connected by piston rods or bolts 17 with a piston 18 having portions 19 and 20 respectively operating in the piston chambers 8 and 9.

Actuating fluid for the pistons is supplied from any suitable source to a coupling nipple 21 formed upon the side of the cylinder 7 and 50 communicating with a passageway 22 that

extends to a valve chest 23 formed on the opposite side of the cylinder member 7. This passageway 22 is in communication with a cylinder 24, in which is a piston 25 that operates in opposition to the piston 18, and is 55 adapted to elevate the same. From the valve chest 23 passageways 26 and 27 lead to the piston chambers 9 and 8 respectively. Communication between the supply passageway 22 and the passageways 26 and 27 is controlled by a suitable valve 28 in the valve chest. It is believed to be unnecessary to go into detail regarding this valve as its structure and operation is well known. The valve 60 is connected to a suitable operating handle 29 at one side of the cylinder 7. It will be evident, however, that when the valve is operated to open the passageways 26 and 27 to the supply passageway 22 motive fluid will enter the piston chambers 9 and 8 and move the piston 18 downwardly against the action of the piston 25. On the other hand when the supply to the chambers 8 and 9 is cut off and said chambers are open to the exhaust, 65 then the piston 25 will elevate the piston 18. As a consequence the upper die carrier 14 and its dies 15 and 16 are raised and lowered, and when in lowered position, cooperate with the lower dies 12 and 13.

The present invention relates to a means 70 for cleansing the dies of scale and like materials which accumulate in the lower or stationary dies particularly. To this end the head 10 is vertically bored at one or more places as shown at 30, and in these bores are 75 located vertically sliding stems 31 that are interposed between the upper piston 20 and the upper die member or carrier 14, abutting the same so that the stems will move with the piston and die carrier. These stems are 80 provided with longitudinal passageways 32 terminating in laterally inclined ports 33 that open through the sides of the stem adjacent their ends. The length of each passageway 32 is greater than the thickness of 85 the head 10 but the ports 33 are so located that they alternately enter the heads as shown particularly in Figures 4 and 5.

The operation of these devices is as follows: When the die members are open, or as 90

shown in Figure 4, the lower ports 33 will be in the head 10. If now motive fluid, such as air, is turned into the passageway 26, the piston 18 is forced downwardly, thereby correspondingly moving downwardly the head 14. The stems 31 are also moved downwardly and as they do the ports 33 will enter the piston chamber in which the fluid under pressure is located before the upper ports 33 enter the head 10. There is consequently an escape of fluid through the passageway 32 and upper ports 33, these latter being downwardly inclined. Jets of air are blown over the surface of the head 10 and the dies mounted thereon, so that the scale which has been deposited in these dies and on the head is blown away. As the ports continue their downward movement, the upper ports 33 will enter the head 10 and the escape of the fluid from the piston chamber 9 is stopped. Consequently full force of the motive fluid in the piston chamber is acting on the piston when the dies are in their clamping or cooperating relation.

25 From the foregoing, it is thought that the construction, operation, and many advantages of the herein described invention will be apparent to those skilled in the art without further description and it will be understood that various changes in the size, shape, proportion and minor details of construction may be resorted to without departing from the spirit or sacrificing any of the advantages of the invention.

25 What I claim, is:

1. In metal working apparatus, the combination with a cylinder member having an upper head and a piston operating in the cylinder member, of a fixed die overlying the cylinder member, a movable die overlying the fixed die and movable toward and from the same, a piston rod connection between the piston and movable die, and a stem interposed between the piston and movable die for movement therewith and having a passageway that opens into the cylinder member for receiving fluid therefrom, said passageway directing fluid against one of the dies to clean the same.

53 2. In metal working apparatus, the combination with a cylinder member having a piston chamber and an upper head and a piston operating in the cylinder member, of a fixed die overlying the cylinder member, a movable die overlying the fixed die and movable toward and from the same, a piston rod connection between the piston and movable die, and a stem interposed between the piston and movable die for movement therewith and having a passageway provided with a port movable into and out of the piston chamber and into and out of the head, said passageway having an outlet port that opens between the dies and directs fluid thereagainst to clean the dies.

3. In a metal working apparatus, the combination with relatively movable die members, of a fluid operated motor connected thereto for moving the same, and means independent of the motor and its connection with the die members, but movable therewith, for directing fluid from the motor to the dies to clean the latter.

4. In a metal working apparatus, the combination with a fixed die member and a movable die member co-operating therewith, of a motor for moving the movable die member, including a cylinder and a piston operating in the cylinder and attached through suitable connections to the movable die member, and means independent of the motor and its connection with the movable die member, but movable therewith, for delivering cleansing fluid from the cylinder to the dies.

5. In a metal working apparatus, the combination with a fixed die member and a movable die member co-operating therewith, of a motor for moving the movable die member, including a cylinder and a piston operating in the cylinder and attached through suitable connections to the movable die member, means independent of the motor and its connection with the movable die member, but movable therewith, for conducting cleansing fluid from the cylinder to the dies, and said means being movable to functioning positions during the initial movement of the movable die member.

6. In a metal working apparatus, the combination with a fixed die member and a movable die member co-operating therewith, of a motor for moving the movable die member, including a cylinder and piston operating in the cylinder and connected to the movable die member through a piston rod, and a device independent of the motor and rod and interposed between the piston and movable die member for movement therewith for delivering cleansing fluid to the dies during the movement of the movable die member.

7. In a metal working apparatus, the combination with a cylinder having a head, of a piston operating in the cylinder, a fixed die, a movable die connected to the piston through a rod and co-operating with the fixed die, and a stem independent of the foregoing elements slideable in the cylinder head and having a passageway that opens into the cylinder and into the space between the dies, said stem being movable with the piston and movable die.

8. In a metal working apparatus, the combination with a cylinder member having an upper head and a piston operating in the cylinder member, of a fixed die overlying the cylinder member, a movable die overlying the fixed die and connected through suitable elements to the piston for movement towards and from the fixed die, and a stem independent of the connections between the movable die

and piston and slidably passing through the head and extending between the piston and movable die, said stem having a passageway that opens into the cylinder member and into the space between the dies to direct fluid from the cylinder member through the head and against the dies for cleaning the same.

9. In a metal working apparatus, the combination with a cylinder member having a piston chamber, of a piston operating in the chamber, co-acting die members, one of which is fixed and the other movable, connections between the piston and the movable die for effecting its movement during the movement of the piston, means for directing active fluid to the piston chamber to actuate the piston, and means separate from the piston and its connection with the die and movable therewith for directing a portion of the fluid from the piston chamber to the dies for cleansing them, said means being closed against operation when the dies are in a predetermined relation.

10. In a metal working apparatus, the combination with a cylinder member having a piston chamber, of a piston operating in the chamber, co-acting die members, one of which is fixed while the other is movable, said movable die being connected to the piston through suitable rods to effect its movement with the piston, means for directing motive fluid to the piston chamber to actuate the piston, and a device movable with the piston and independent of its connection with the movable die and having a passageway for permitting a portion of the fluid to escape from the piston chamber to the dies for cleansing the latter, said passageway being closed when the dies are in certain predetermined relation.

40 11. In a metal working apparatus, the combination of a pair of co-acting die members, one of which is movable, of a fluid operated motor connected to the movable die member for moving the same, and means independent of the motor and the movable die and their connection, but movable by either, for conducting fluid from a source to the die member for cleaning the same.

50 In testimony whereof, I affix my signature.
GUSTAV C. PEARSON.
